UNITED STATES PATENT OFFICE.

J CLIFFORD SMITH, OF BELLFLOWER, CALIFORNIA, ASSIGNOR OF ONE-HALF TO ELI DICKMAN, OF LA HABRA, CALIFORNIA.

ROD GUIDE.

Application filed August 3, 1926, Serial No. 126,843. Renewed August 21, 1928.

This invention relates to rod guides and more particularly to a guide for the sucker rods of deep wells.

As is well known to those familiar with the art, in the boring of deep wells, it is extremely difficult and in fact practically impossible to obtain a straight bore, with the result that when the pump tubing is inserted in the well and the pump rods directed therethrough, these rods will engage against the sides of the tubing at a number of points. Since the sucker rod is under considerable strain and is of relatively small size, the friction between the walls of the tubing has a tendency to destroy both the sucker rod and tubing. Devices have been constructed for the purpose of maintaining the sucker rods in spaced relation to the walls of the tubing, but all of these devices with which I am familiar either interfere materially with the upward passage of the fluid or have parts which, as the guide becomes worn, are liable to separate from the sucker rods and fall down the tubing, so that they enter the pump and cause considerable damage thereto. An important object of this invention is to provide a device which is free from parts which are liable to separate or become broken and fall into the well and which does not interfere to any appreciable extent with the upward passage of the fluid.

A further object of the invention is to provide a device of this character which may be employed as a coupling for the adjacent ends of sucker rod sections.

These and other objects I attain by the construction shown in the accompanying drawings, wherein for the purpose of illustration is shown a preferred embodiment of my invention and wherein:

Figure 1 is a fragmentary side elevation partially broken away of a sucker rod line embodying guides constructed in accordance with my invention;

Figure 2 is a vertical sectional view taken through one of the guides;

Figure 3 is a section on the line 3—3 of Figure 2;

Figure 4 is a fragmentary side elevation of one of the tubes which is employed in the construction of the guide.

Referring now more particularly to the drawings, the guide comprises a tubular body 10 of slightly less diameter than the tubing

11 which is being employed in the well and 55 having at its ends boxes 12 for the reception of pins 13 on the adjacent ends of sucker rod sections 14. The boxes 12 are of considerably less diameter than the tubing and the ends of the cylindrical body converge upon the boxes, 60 as at 15. The converging walls 15 are formed with a plurality of openings 16 permitting passage of the fluid through the cylindrical body. A rod 17 of the same size as that ordinarily employed in the construction of the 65 sucker rods preferably connects the boxes 12 so as to rigidify the structure.

In constructing the guide section, the boxes 12 are preferably connected by the rod 17 and a piece of pipe of proper diameter for 70 the formation of the cylindrical body is provided and the ends thereof provided with notches 18 forming fingers 19. The ends of these fingers are bent inwardly until they contact against the boxes and are welded to 75 the boxes, so that an integral structure is provided. It is pointed out that a guide of this character may wear away entirely along one side face thereof without the production of any portions which will fall into the well and 80 interfere with the operation of the pump. Since the guide is of substantially the same diameter as the internal diameter of the pipe, it will follow that the walls of the guide will have contact with the walls of the tubing for 85 a considerable area, thus distributing the thrust of the rods in such fashion that wear at any one given point is materially reduced.

Since the construction hereinbefore set forth is obviously capable of a certain range 90 of change and modification without materially departing from the spirit of the invention, I do not limit myself to such specific structure except as hereinafter claimed.

I claim:

A sucker rod guide comprising a hollow body having diametrically reduced cylindrical end portions and a cylindrical intermediate portion, the said end portions being joined with the intermediate portion by 100 shoulders which are ogee in vertical transverse section, portions of the shoulders lying within the ends of the radii of the end portions of the body and the said shoulders being provided with openings.

In testimony whereof I hereunto affix my signature.

J CLIFFORD SMITH.
